H. M. MOORE

FENCE WIRE STRUCTURE

Filed Jan. 12, 1927

Inventor
H. M. Moore

By Clarence A. O'Brien, Attorney

Patented Apr. 3, 1928.

UNITED STATES PATENT OFFICE.

HARRY M. MOORE, OF ELMIRA, MISSOURI.

FENCE-WIRE STRUCTURE.

Application filed January 12, 1927. Serial No. 160,650.

This invention relates to an improved device which is frequently referred to in the art as a fence wire stretcher; that is, a device which is secured upon a fence post and which is connected with the fence wires to draw them in a longitudinal direction through the medium of suitable means, whereby they can be fastened in a taut condition upon said post.

My principal aim is to generally improve upon devices of this class by providing one which is structurally different from known patented and marketed devices, the arrangement being such as to facilitate manufacture from a standpoint of assemblage, and to obtain efficiency in operation due to the ease of manipulation.

Briefly, the invention comprises a substantially V-shaped frame having spur plates at one end to be engaged with the fence post, and having a lever actuated rack bar and retaining pawl mechanism at its opposite end, together with means for connecting said mechanism with the fence wires.

In the drawings:—

Figure 1 is a side view showing the device in use.

Fig. 2 is a longitudinal section through the same, showing the details more plainly.

Fig. 3 is a cross section.

Referring now to the drawing in detail, it will be seen that the reference character 1 designates the fence wires adapted to be connected to the post 2. A clamping device 3 is connected to the wires in any appropriate manner, the same being of suitable construction.

The clamping device here shown, is provided with chains 4 including a central connecting ring 5 which operates in a manner to be hereinafter described.

The wire stretcher is generally designated by the reference character 6, and it is preferably composed of a pair of angle irons 7 arranged in divergent relation to provide the so-called V-shaped frame. At the inner ends of these angle irons, are pointed plates 8 which operate to bear against the fence post in the manner indicated in Fig. 2.

Connected to the last named end portions of the angle irons is a cross-brace 9 of general U-shaped form, the same being riveted or otherwise rigidly secured in place. Secured between the converging ends of the bars is a solid body 10 of appropriate configuration having an apertured lug 11 at one

end and having its opposite end bifurcated as at 12. This body is formed with a longitudinal passage through which a rack bar 13 slides. Operatively engaged as at 14, with this bar is an operating lever 15 whose forked end is pivotally connected with the bifurcations 12 through the medium of a link 16.

Slidably mounted in the body and movable at right angles to the teeth of the rack bar is a spring pressed pawl 17 including a stem 18 connected to a retainer. This retainer is here shown as including a handle 19 and a plate-like portion 20. As shown in Fig. 2, the body is formed with a recess into which this retainer may be dropped to move to operative position. By grasping the handle 19 and pulling the pawl 17 outwardly against the tension of the spring, however, and turning the part 20 to extend across the recess, the pawl is held in a disengaged position.

A chain 21 is connected with the rack bar, and is provided with a hook 22 to engage in the aforesaid eye or ring 5. In operation, the device is arranged somewhat as represented in Fig. 1, and in this connection I might state that I prefer to provide an extra chain 23 which is connected with a stake 24 driven in the ground to steady the device. The spur plates 8 are placed against the post and assuming that the clamp 3 is in place on the fence wires 1, the hook 22 is engaged with the eye 5, thus rendering the device ready to stretch the wires. Obviously, by actuating the lever 15 in a direction from left to right in Fig. 2, the rack 13 will be fed through the opening in the body 10 and the pawl will serve to hold it in the position to which it has been moved. In this way the wire will be stretched sufficiently taut to permit it to be nailed upon the post in an obvious manner.

It is believed, that by considering the description in connection with the drawings, a clear understanding of the construction, as well as the operation and use of the invention will be clear. Therefore, a more lengthy description is thought unnecessary.

Having thus described my invention, what I claim as new is:—

In a wire stretcher, a frame of general V-shaped configuration composed of a pair of angle irons, a cross brace connected to the diverging end portions of said irons, spur plates carried by the last named ends

of said bars, a body disposed between and connected to the opposite ends of said irons, said body having a passage extending therethrough, a toothed rack bar slideable through said passage, a chain connected to the inner end of said rack bar, a hook carried by the free end of said chain, an operating lever for said rack bar, a link pivotally connected to

said lever and to said body, a spring pressed pawl mounted upon said body and movable at right angles to said rack bar for engaging the teeth of the latter, and a rotary retainer carried by said pawl.

In testimony whereof I affix my signature.

HARRY M. MOORE.
